ABSTRACT

Wires for terminal application are sequentially loaded into slots of an elastomeric conveyor belt at a loading station, the loading being facilitated by a swingable arm which forces a wire into the bottom of a slot at the loading station, and thereafter the conveyor belt is advanced to bring into position a new slot at the loading station and subsequently thereto a terminal is applied to the leading end of a wire at a guarded terminal applying station. The swingable arm which facilitates the loading of the wires into the slots at the loading station is so designed that it will move with relatively little force during an initial part of its movement and with relatively greater force during the final part of its movement as it approaches the slots.

MANUALLY LOADED TERMINAL APPLICATOR

FIELD OF THE INVENTION

This invention relates generally to a terminal applicator for crimping an electrical terminal on the end of a wire, and more particularly to a manual assist feed mechanism of type shown in the aforementioned co-pending application in which novel means are provided for facilitating the loading of wires into the slots of an elastomeric belt and also in which novel control and drive means are provided.

BACKGROUND OF THE INVENTION

U.S. Pat. No. 3,804,603 issued Apr. 16, 1974 discloses an apparatus including a terminal applicator or crimping press, a loading zone, and a conveyor which transports wires from the loading zone to the terminal applicator, the conveyor constituting an endless belt having spaced apart wire receiving slots extending transversely thereon, the slots opening onto the outer periphery of the belt and the belt being mounted for rotation on a pair of longitudinally spaced sprockets and having an upper longitudinal run which extends from the loading zone or station to the terminal applying apparatus or station. The foregoing patent application also discloses an extended wire supporting surface which extends longitudinally away from the conveyor at the loading station, the wire supporting surface lying below the upper periphery of the run which extends from the loading station to the terminal applying station. The slots in the conveyor belt which receives the wires are open adjacent the wire supporting surface and the wires are sequentially disposed within the open slots. Subsequently the conveyor is caused to be moved towards the discharge station and a roller contacts a wire as the conveyor is being moved to force the wire into the bottom of a slot. After the completion of the movement of the conveyor the terminal applicator is caused to be operated.

While the foregoing apparatus performs generally satisfactorily it has been found in practice that it is not adaptable to many forms of presses which apply terminals as there is interference between the extended wire supporting surface and the press. Furthermore, the prior art device was developed to run continuously and it is desirable to add greater operator flexibility to the operation of the machine.

OBJECTS AND SUMMARY OF THE INVENTION

It is an object of the present invention to provide, in a manually loaded terminal applicator having a conveyor which extends between a loading station and a guarded terminal applicator, improved means for positioning a wire into a slot of the conveyor belt and also which has differing available modes of operation to suit the convenience of the operator.

More specifically, it is an object of the present invention to provide in apparatus of the aforesaid type, means to position a wire into a slot of an elastomeric conveyor belt including wire engaging means and moving means operable to move said wire engaging means from a first position remote from the slot to a second position adjacent the bottom of the slot, the moving means as it moves from its first position to its second position initially moving at a relatively high rate of speed with relatively little force and finally moving at a relatively low rate of speed with relatively high force.

It is another object of the present invention to provide novel control means for an apparatus having a terminal applying means at a terminal applying station, a loading station, a conveyor extending between the two stations, and reciprocal positioning means disposed at the loading station, the control means being operable to sequentially initiate movement of the reciprocal positioning means, the conveyor, and the operation of terminal applying means at the terminal applying station.

These and other objects and advantages of the present invention are accomplished by providing an apparatus having a terminal applicator at a terminal application station, a loading station remote from the terminal applying station, a slotted conveyor which runs from the loading station to the terminal applying station, and reciprocal wire positioning means including a pivoted clamp arm having a wire engaging portion movable from a first position remote from the bottom of a conveyor slot at the loading station to a second position adjacent the bottom of the slot, and a pressure arm which slidably engages the clamp arm and is movable in such a manner that it initially causes the wire engaging portion of the clamp arm to move at a relatively high rate of speed with little force and finally to move, as the clamp arm approaches the bottom of the slot at a relatively low rate of speed with high force. The apparatus further includes control means which are operable to first initiate movement of the clamp arm, and then the conveyor, and finally initiate operation of the terminal applying means, the movement of the clamp arm being initiated while the conveyor is at rest, the movement of the conveyor being initiated after the clamp arm has completed its movement towards the second position, and the operation of the terminal applying means being initiated after the conveyor has completed its movement to present a new slot at the loading station, the operation of the terminal applying means causing a terminal to be applied to the leading end of the wire. The control means includes a single revolution clutch which causes an output shaft to rotate one revolution, the output shaft being coupled with an intermittent drive to drive the conveyor belt during a portion of the movement of the output shaft, and the output shaft also carrying rotary cams which are contacted by micro switches, one of the micro switches being coupled to a rotary solenoid which initiates movement of the clamp arm prior to the movement of the conveyor and the other micro switch being coupled to the terminal applicator to cause the terminal applicator to be operated after the completion of the movement of the conveyor.

The foregoing and other objects and features will be apparent to those skilled in the art after a consideration of the following detailed description taken in conjunction with the accompanying drawings in which a preferred form of this invention and various control systems are shown.

DESCRIPTION OF THE DRAWINGS

FIG. 1 is a perspective view of an apparatus in which the principles of the present invention are incorporated.

FIG. 2 is a front sectional view of a portion of the machine shown in FIG. 1.

FIG. 3 is a top view of the structure shown in FIG. 2.

FIGS. 4 and 5 are front sectional views of the wire positioning means, FIG. 4 shows the wire positioning means in a first position remote from the bottom of a

conveyor slot at the loading station, and FIG. 5 showing the wire positioning means in a second position adjacent the bottom of the conveyor slot.

FIGS. 6 and 7 are schematic illustrations of two of the various control modes of the apparatus of the present invention, FIG. 6 illustrating how the machine is controlled by a sensor plate, and FIG. 7 illustrating how the machine may be controlled through a foot switch.

DETAILED DESCRIPTION

Turning to the drawings, there is illustrated in FIG. 1 the improved manually loaded terminal applicator of the present invention, which is indicated generally at 10 and which includes a press 12 mounted on a bench or like suitable horizontal support 14, with the operator normally sitting or standing in front of the press and facing the same, that is facing a front wall 16 of a housing, indicated generally at 18, the upper surface 20 of the housing 18 serving as a support for wires after terminals have been applied thereto. Press 12 is operatively coupled to a terminal applicator which may be of the type shown in U.S. Pat. No. 3,343,398 issued to David Ronald Kerns, Sept. 26, 1967, and assigned to the common assignee, the applicator being disposed behind a rectangular shield 22.

The press 12 includes a reciprocal press ram 24 to which is operatively coupled a depressible applicator die 26 (FIG. 2), the die cooperating with a fixed anvil 28 to crimp the barrel portion of a terminal to the leading end of a wire carried by conveyor 30. The area defined by the applicator die 26, the anvil 28 and that portion of the conveyor which is in line with these parts can be considered to be the terminal applicator station.

The press 12 and the applicator including the applicator die 26 and anvil 28 form no part of the present invention and the operation of the same may be evident by reference to previously mentioned Kerns U.S. Pat. No. 3,343,398. However, it should be noted that the press includes an electric motor which rotates a fly wheel, the fly wheel in turn being coupled by means of a single revolution clutch to the press ram 24 causing in turn cyclical operation of the applicator die 26 which completes a crimping operation by crimping a U-shaped barrel of a terminal about the bared end of a wire. The single revolution clutch is energized by electric control means. The terminals are supplied in strip form 32 to the applicator from a reel 34.

The conveyor 30 is an endless elastomeric belt having a plurality of transverse longitudinally spaced slots 36 having an open upper end 38 (FIG. 4) and a closed lower end 40. The lower side of the belt is formed with cogs 42 which mesh with corresponding cogs or teeth 44 on right and left hand sprockets 46, 48. Each of the sprockets 46, 48 is in turn mounted for rotary movement on a support 50, 52, respectively, which is in turn interconnected with the bench 14 for adjustable movement in a manner not material to the present invention. The slots 36 will be open as they pass over the sprockets 46, 48 and will be closed in either the upper run 54 or the lower run 56 between the two sprockets 46, 48. The conveyor is more fully described in U.S. Pat. No. 3,804,603.

The loading station includes a member having an upper angled surface 58 having slots 59, a downwardly extending portion of the member to the right of the surface 58 defining a V-shaped opening 60 between the right hand end of the upper angled surface member 58

and a slotted side plate 62, the slotted side plate extending rearwardly from the left hand side of the shield 22. Wires 64 which are to be conveyed to the terminal applicator station are initially dropped through the slot 60 at which time they will lay on top of the open upper end 38 of a slot disposed at the loading station as can best be seen in FIG. 4.

In order to insure that the wires are fully moved to the bottom of the slot 36 reciprocal means are provided 10 to force the wires into the bottom of the slot. This structure includes a clamp arm 66 which is pivoted at one end 68 to the rear side of the shield 22 by means of a pivot pin 70. The other end of the clamp arm carries wire engaging means in the form of two spaced 15 apart fingers 72, 74. The clamp arm is mounted for movement between a first position shown in FIG. 4 to a second position shown in FIG. 5. The fingers 72, 74 are adapted to pass through slots 76, 78 in the slotted side plate 62 and the slots 59 in surface 59 as the arm 20 66 moves between the first and second positions, the forward end of the fingers extending downwardly and engaging the wire immediately to either side of the conveyor belt 30 as the clamp arm completes its movement to the second position as can best be seen from FIGS. 25 3 and 5.

A pressure arm 80 is pivotally secured at one end 82 by means of a pivot pin 84 to the shield 22 and carries a roller 86 which is rotatably journaled by a pivot pin 88 at the other end of the arm, the roller 86 being 30 adapted to slidably engage the upper surface 90 of the clamp arm. The pressure arm initially defines an acute angle with the clamp arm when in the first position and a greater angle when in the second position as can be seen from an inspection of FIGS. 4 and 5. As the angle 35 approaches a right angle the clamp arm will be moved at a slower rate but with higher force. The pressure arm 80 forms part of moving means for moving the clamp arm 66 from the position shown in FIG. 4 to the position shown in FIG. 5, and the moving means further includes a rock shaft 92, a rock arm 94, and a link 96, one end of the link being secured to the rock arm 94 by a ball joint 98, and the other end of the link 96 being secured to an intermediate portion of the pressure arm by pivot means 100. The rock shaft 92 is caused to rock 40 by means of a rotary solenoid 102 (shown in phantom in FIGS. 4 and 5). The rotary solenoid 102 is mounted on the forward side of the shield 22 and its rock shaft extends through the shield as can best be seen from FIG. 3.

The drive to the conveyor 30 is from a variable speed electric motor 104 which is mounted within the right hand end of the housing 18 as can best be seen from FIGS. 2 and 3. The output shaft of the motor 104 is in turn connected to a right angle gear box 106 having an output shaft 108. A sprocket 110 is mounted on the output shaft 108 and in turn drives a drive chain 112, the other end of which is trained over a sprocket 114, the sprocket 114 being interconnected with the input 55 of a single revolution clutch assembly 116 in a manner not material to the present invention. The single revolution clutch assembly 116 is provided with an output shaft 118 which extends to either side of the assembly 116 as can best be seen from FIG. 3. A solenoid 120 (FIGS. 6 and 7) is employed for controlling the operation of a single revolution clutch (not shown) within the assembly 116 and it should be noted that if the solenoid 120 is moved to an operative position it will cause 60 65

the single revolution clutch to interconnect the power input provided by the sprocket 114 with the output shaft 118 to cause the output shaft to rotate one revolution.

Intermittent drive means 122, which may be of a Geneva type movement, interconnect the output shaft 118 of the single revolution clutch assembly with the conveyor belt 30. To this end, the forward side of the output shaft 118 is provided with a sprocket 124 and one end of a drive chain 126 is disposed about the sprocket 124, the other end of the drive chain 126 being disposed about a sprocket 128 mounted upon as input shaft 130 to the intermittent drive means 122. The intermittent drive means 122 is also provided with an output shaft 132 which carries a sprocket 134, there being a drive chain 136 which has a portion disposed over the sprocket 134 and another portion disposed over sprocket 138 which is secured to shaft 140, the shaft 140 also being coupled to the drive sprocket 46 of the conveyor 30. It should be noted that sprocket 128 and 124 each have the same number of teeth and thus one revolution of the shaft 118 will cause the input shaft 130 to also rotate one revolution. The intermittent drive means is so selected that the output shaft will be caused to rotate only during 90° of rotation of the input shaft 130 and thus, the conveyor will only move during a portion of a complete rotation of the shaft 118. The timing of the intermittent drive means could be such that the conveyor would rotate during any 90° of revolution of the output shaft 118 of the single revolution clutch. However, in the embodiment shown the conveyor is caused to be moved as the output shaft 118 rotates from a 90° position to 180° position away from its starting point.

Two rotary cams are also mounted on the output shaft 118, one rotary cam 142 being mounted on the front side of the shaft 118 and the other rotary cam 144 being mounted on the rear side of the shaft 118. A micro switch 146 is mounted on the forward side of the single revolution clutch assembly 116 and has a cam follower 148 which engages the rotary cam 142, the cam 142, cam follower 148, and micro switch 146 so being arranged that the switch will be closed when the rotary shaft has rotated 30 degrees and will remain closed until it rotates 120° from its starting position, the switch then being open during the balance of the rotation of the output shaft 118. The switch 146 is in turn interconnected with the rotary solenoid 102 and causes the output shaft 92 of the solenoid to be rotated in one direction when the switch is closed and to be rotated in an opposite direction when it is open. This will cause the clamp arm 66 to be moved from its first position shown in FIG. 4 to its second position shown in FIG. 5 when the switch is closed and will cause the clamp arm 66 to return to its first position after the switch is opened upon completion of 120° of revolution of the output shaft 118. In this connection it should be noted that a tension spring 150 is provided to return the clamp arm 66 to its first position upon reverse movement of the output shaft 92 of the solenoid.

A second micro switch is mounted on the rear side of the single revolution clutch assembly 116 and also carries a cam follower (not shown) which is adapted to contact the rotary 144. These parts are so arranged that the switch 152 will be closed after the output shaft 118 has rotated 200° and the switch will then be opened after the shaft is rotated approximately 300°. The

switch 152 controls the operation of the press 12 through the electrical control means of the press which energizes the single revolution clutch within the press.

As should be evident from the foregoing, the cam 142, 144, micro switches 146, 152 and the intermittent drive means 122 act as control means which are operable to sequentially initiate movement of the reciprocal positioning means or clamp arm 66, the conveyor 30, and also to control the operation of the terminal applying means. The movement of the reciprocal positioning means is initiated after the output shaft 118 of the single revolution clutch has rotated 30° and holds the clamp arm down in its lowered second position until after the shaft has rotated 120°. The movement of the conveyor 30 is initiated after the reciprocal positioning means has completed its movement towards the closed side of the slot 36 disposed at the loading station and thus, is initiated after the output shaft has been rotated 90°. The movement of the belt is completed after the output shaft has rotated 180° and the parts are so timed that a new slot 36 will be presented at the loading station at this point. Thereafter, when the output shaft has now rotated 200°, the operation of the terminal applicator will be initiated to apply terminals at the terminal applying station, and the press will complete its operation before the shaft 118 has completed one revolution.

The wires with the terminals affixed thereto are discharged onto the wire support 20. In this regard, it should be noted that the housing 18 is provided with an upper sloping portion 154 that is provided with a slot 156 through which the discharge side of the conveyor belt passes. The leads which extend to either side of the belt will be stripped from the conveyor as the slots are opened as they pass over a sprocket 46 and will slide down the inclined surface 154 to the wire support surface 20. In the event that the slot 36 of the belt 30 which is in alignment with the terminal applying station does not carry a lead, there is provided a micro switch 158 carrying a sensor 160. If the sensor feels a wire the operation of the press will be initiated, however, if no wire is present then the operation of the press will not be initiated.

During the operation of the apparatus the motor 104 will always be in operation. However, a cycle of operation will not be initiated unless the single revolution clutch in the clutch assembly 116 is caused to interconnect the input from the motor with the output shaft 118. As previously noted a solenoid 120 is used to cause the clutch to interconnect the input with the output shaft. Three differing modes may be employed in the overall operation of this apparatus. According to a first mode the operator will insert a wire against a wire and sensor plate which will in turn initiate operation of the solenoid 120; according to a second mode the operator inserts the wire against a wire end positioning plate and then actuates a foot switch which in turn controls the solenoid to produce one complete cycle of the unit; and according to a third mode of operation the solenoid 120 is held in its closed position at all times so that the output shaft 118 runs constantly and the feed of the motor may be varied so that the overall feed rate may be adjusted to the individual operator's ability with the wire insertion timed to the cycling of the machine.

FIG. 6 schematically illustrates the first of these various modes of causing the apparatus to cycle and to this end it should be noted that the bared end 162 of a wire 64 is brought into contact with a sensor plate 164

which is located to the rear of the V-shaped opening as can best be seen in FIG. 3. The sensor plate is in turn interconnected with electronic switching apparatus 166 through an electrical conductor, 168, the electronic switching apparatus sensing the change in the capacitance of the sensor plate when it is contacted by the bared wire 162 and in turn initiating the operation of the solenoid 120.

The second of the various modes of operation is illustrated in FIG. 7 and to this end it should be noted that a foot switch 170 (also shown in FIG. 1) is provided, the operator merely stepping on the foot switch which is interconnected through an electrical lead 172 to the solenoid 120 to initiate cycling of the apparatus. In this mode a wire locating plate 174 is substituted for the sensor plate 164 and is positioned in the same location as the sensor plate 164 as shown in FIG. 3. Thus the operator would place the wire 64 into the V-shaped slot and bring the bared end 162 into contact with the wire locating plate 174 at which time the operator would then step upon the foot switch 170 to initiate a cycle of operation.

In the final mode of operation the switch to the solenoid is always closed and the machine repetitively cycles at a rate comfortable to the operator. Again the wire will be dropped into the V-shaped slot and the bared end 62 would be brought into contact with a wire locating plate 174 before the conveyor movement is initiated.

The apparatus for conveying wires to a terminal application location of a press may be used with differing presses and applicators such as end feed or side feed applicators. As it may be used with differing presses and applicators, adjustable support means 176 are provided for adjustably locating the various components on a bench 114. The adjustable mounting means are not a material part of this invention and thus will not be described in detail.

While the preferred structure in which the present invention have been incorporated is shown and described above, along with the various alternative operating modes, it is to be understood that the invention is not to be limited to the particular details, shown and described above, but that, in fact, widely differing means may be employed in the practice of the broader aspects of the invention.

What is claimed is:

1. In an apparatus for applying terminals to the ends of wires including a terminal applying station, a loading station, and a conveyor extending between said loading station and said terminal applying station and having transverse longitudinally spaced slots adapted to receive wires therein at said loading station, each slot being defined by elastomeric material and having an open side and an opposed closed side;

the combination therewith of

means to position a wire into a slot at said loading station, said means comprising

wire engaging means, and

means operable to move said wire engaging

means from a first position remote from the closed

side of a slot at said loading station to a second position adjacent said closed side, said wire engaging

means forcing said wire into contact with the closed side of said slot as it moves towards its second position.

2. The apparatus set forth in claim 1 in which said wire engaging means includes a clamp arm pivoted adjacent one end and having an engaging portion adjacent the other end.

5 3. The apparatus set forth in claim 2 in which said engaging portion of the clamp arm has two fingers spaced apart from each other a distance slightly in excess of the length of a slot.

4. The apparatus set forth in claim 1 in which said 10 moving means as it moves from its first position to its second position initially moves said wire engaging means at a relatively high rate of speed with relatively little force and finally moves the wire engaging means at a relatively low rate of speed with relatively high force.

15 5. The apparatus set forth in claim 4 in which said wire engaging means includes a clamp arm pivoted adjacent one end and having a wire engaging portion adjacent the other end.

20 6. The apparatus set forth in claim 5 in which said moving means further includes a pressure arm pivoted at one end, the other end of said pressure arm slidably engaging the clamp arm adjacent the pivoted end of said clamp arm and originally defining an acute angle with the clamp arm when the moving means is in its first position, said pressure arm sliding towards an intermediate portion of the clamp arm and defining a greater angle with the clamp arm than the original acute angle as the moving means approaches its second position.

25 7. The apparatus set forth in claim 6 in which said moving means further includes a rock shaft, a rock arm having one end mounted upon said shaft, and a link extending from the other end of said rock arm to an intermediate portion of said pressure arm.

30 8. An apparatus for applying terminals to the ends of wires comprising:

a terminal applying station including terminal applying means operable to apply a terminal upon the end of a wire;

a loading station;

an endless elastomeric conveyor having a run movable from said loading station to said terminal applying station and having transverse longitudinally spaced slots adapted to receive wires therein at said loading station, each slot having an open side and an opposed closed side;

reciprocal positioning means operable to position a wire adjacent the closed side of a slot at said loading station as said reciprocal positioning means completes its movement towards the closed side of the slot; and

control means operable to sequentially initiate movement of the reciprocal positioning means and the conveyor, and the operation of the terminal applying means, the movement of the reciprocal positioning means being initiated while the conveyor is at rest, the movement of the conveyor being initiated after the reciprocal positioning means has completed its movement towards the closed side of a slot, and the operation of the terminal applying means being initiated after the conveyor has completed its movement to present a new slot at the loading station, the operation of the terminal applying means causing a terminal to be applied to the leading end of a wire.

9. The apparatus set forth in claim 8 in which said reciprocal positioning means moves between a first position remote from the closed side of said slot to a second position adjacent said closed side, said reciprocal positioning means initially moving at a relatively high rate of speed with relatively little force as movement away from said first position is initiated and said reciprocal positioning means moving with a relatively low rate of speed and relatively high force as movement towards its second position is completed.

10. The apparatus set forth in claim 9 in which reciprocal positioning means includes a clamp arm pivoted adjacent one end and having a wire engaging portion adjacent the other end, a pressure arm pivoted at one end, the other end of the pressure arm slidably engaging the clamp arm adjacent the pivoted end of said clamp arm and originally defining an acute angle when said reciprocal positioning means is in its first position, said pressure arm sliding towards an intermediate portion of the clamp arm and defining a greater angle with the clamp arm than the original acute angle as the reciprocal positioning means approaches its second position.

11. The apparatus set forth in claim 8 in which said

control means includes a foot switch.

12. The apparatus set forth in claim 8 in which said control means includes a sensor plate disposed to one side of said loading station.

5 13. The apparatus set forth in claim 8 in which said control means includes constantly running drive means, a single revolution clutch coupled to said drive means and having an output shaft coupled to said single revolution clutch, intermittent drive means coupled to

10 said output shaft and said conveyor and operable to move the conveyor only during a portion of a revolution of the output shaft, and further means coupled to said output shaft and operable to initiate operation of the reciprocal positioning means prior to the movement of the conveyor and to initiate operation of the terminal applying means after the completion of movement of the conveyor.

15 14. The apparatus set forth in claim 13 in which said further means coupled to said output shaft includes two rotary cams and two micro switches, and in which said reciprocal positioning means includes a rotary solenoid coupled to one of said micro switches.
